UNITED STATES PATENT OFFICE.

HENRY SCHWARBER, OF WEEHAWKEN, NEW JERSEY, ASSIGNOR TO INFLEXIBLE COMPANY, OF WEST NEW YORK, NEW JERSEY.

DESIGN FOR EMBROIDERY.

47,276.

Specification for Design.

Patented Apr. 27, 1915.

Application filed January 23, 1915. Serial No. 4,060. Term of patent 3½ years.

To all whom it may concern:

Be it known that I, HENRY SCHWARBER, a citizen of the Republic of Switzerland, residing at Weehawken, in the county of Hudson and State of New Jersey, have invented a new, original, and ornamental Design for Embroidery, of which the following is a specification, reference being had to the accompanying drawing, forming part thereof.

The figure is a plan view of a portion of embroidery showing my design.

I claim:

The ornamental design for embroidery as shown.

HENRY SCHWARBER.

Witnesses:

THEODORE ROELDEN,
CARL GEORGIS.
